YARN AND MANUFACTURE OF THE SAME

James Morton, Carlisle, England

Application October 14, 1933, Serial No. 693,567
In Great Britain October 26, 1932

8 Claims. (Cl. 117—14)

This invention relates to the mechanical production from chenille or other tufted threads of a novel kind of round yarn or thread (hereinafter referred to as "yarn") for use in the manufacture by weaving, knitting or other known processes of fabrics and materials. The yarn may be coloured or not as desired.

It is known to manufacture so-called "round" chenille, which is tufted thread consisting of two series of short straight yarn tufts and a central binding thread core, one series of tufts extending from the core radially and at right angles to the other series and the tufts of one series alternating with those of the other. It is also known to manufacture "flat" chenille, in which only one series of tufts extend from a central core. In both cases, the chenille may be manufactured by weaving, or otherwise producing, a preparatory cloth and, thereafter, cutting this cloth into narrow strips constituting the chenille. Preparatory cloth for cutting into flat chenille may also consist of binding threads and transverse pile yarns which are secured to the binding threads by adhesive and which, when cut, constitute the tufts.

Chenille is also manufactured by inserting tufts between twisted core threads, which bind the tufts, this kind of chenille being called "twisted" chenille.

In all cases, the tufts are more or less straight, or radial to the core, with their ends exposed; the tufts retain the fibrous twisted appearance got when they are originally spun; they are entirely separate from one another; and the core is, more or less, exposed.

It is customary to make chenille with tufts cut from differently coloured yarns, so that the chenille is differently coloured throughout its length. However, multi-coloured or other tufted thread made mechanically by the existing modes is subject to the disadvantage that its uses are strictly limited, and it cannot be used, generally, for all the purposes for which one can use spun yarns.

It is of course well known to manufacture multi-coloured spun yarns, but the colouring is usually effected by printing. Such printed yarns have the disadvantage that the colours blend into one another unsatisfactorily, and it is impracticable to obtain a sharply defined colour-junction. The chief object of my invention is to provide an improved yarn having a substantial compact round-section body and being suitable for many of the uses to which ordinary spun yarn can be put, including use as warp and weft in weaving.

The improved yarn is composed of chenille or

other tufted thread whose tufts are wrapped and inter-engaged or united about a core in such manner as to produce a felted or matted surface. The tufts are so wrapped round the core as to merge, more or less, into one another and completely cover the core.

The method whereby the improved yarn is manufactured consists in subjecting a tufted thread to a combined rolling and pressing operation so as to separate the tuft fibres, to crush the fibres of the tufts upon the core and roll them around it, and to force the fibres of adjacent tufts to felt together, or intermingle.

The improved yarn may conveniently be called "rolled" yarn.

The tufted thread used, as aforesaid, for conversion into rolled yarn may be flat or round chenille, no matter how produced.

Apparatus for carrying out the invention includes a pair of members which receive a relative crosswise movement and at least one of which may receive a thread-conveying movement, the said members presenting contiguous rubbing surfaces between which tufted thread is passed lengthwise and pressed.

The invention will now be described, by way of example, with reference to the accompanying diagrammatic drawings, in which:—

Figs. 1 and 2 are a plan and section respectively of a fragment of flat chenille.

Figs. 3 and 4 are corresponding views of a fragment of "round" chenille.

Figs. 5 and 6 are corresponding views drawn to an enlarged scale of a fragment of rolled yarn according to this invention.

Fig. 7 is a plan, also drawn to an enlarged scale, of a fragment of rolled yarn according to this invention and consisting of differently coloured portions.

Figs. 8 and 9 are an elevation and plan respectively of one form of apparatus for mechanically treating the yarn.

Figs. 10 and 11 are corresponding views of another form of apparatus.

Fig. 12 is a plan of yet another form of apparatus.

The fragment of flat chenille shown in Figs. 1 and 2 consists of a series of co-planar tufts 20 of wool or other suitable pile material and a "core" of binding threads 21 interwoven with the tufts, there being three threads 21 in the example shown.

The fragment of round chenille shown in Figs. 3 and 4 consists of two series of tufts 20 and a central core of binding threads 21, the one

series of tufts being arranged at right angles to the other.

The fragments of chenille shown in Figs. 1 to 4 are examples of tufted yarn suitable for use in the manufacture of rolled yarn according to this invention. It must be understood, however, that there may be any desired number of binding threads and the binding may be effected in any appropriate way.

10 In performing the invention, tufted yarn is mechanically treated to separate the twisted fibres of the tufts (the fibres being twisted during the original spinning operations), to crush the tuft fibres upon the core and roll them around it, and to force the fibres of adjacent tufts to felt together, or intermingle. A round yarn having a 15 felted or matted surface is thus produced; and it is found that the tufts maintain the form into which their fibres become set during the mechanical treatment.

15 Figs. 5 and 6 illustrate a plain rolled yarn produced by the mechanical treatment, and Fig. 7 illustrates a rolled yarn having different colours throughout its length, the different colours being 20 conventionally represented by different shadings. This yarn is made from tufted yarn having correspondingly different-coloured tufts. The core threads are again denoted by 21, and the felted, consolidated and fibrous body is denoted by 22. 25 It is found that, in the differently coloured rolled yarn, the adjacent colours are sharply defined, so that this yarn is suited ideally for use in the manufacture of fabrics with sharply defined or intricate designs or patterns, and such fabrics 30 may be woven in an ordinary loom.

With reference now to the apparatus for applying the requisite mechanical treatment to the yarn, a simple form of such apparatus is illustrated in Figs. 8 and 9. The apparatus includes 35 an endless travelling thread-conveying band 30 passing around two rollers or rotatable pulleys 31, the upper stretch of the band passing along the top of a stationary supporting table 32. The apparatus also includes a presser-block 33 which 40 is forced by its weight (or, alternatively, by external adjustable weights or springs) towards that portion of the band 30 which is passing over the table 32. The band is made of rubber, leather or other suitable rubbing material, and the presser-block is faced with such material. The presser 45 block is connected to any appropriate mechanism (such as crank-and-connecting-rod mechanism) for imparting to it a crosswise reciprocatory motion, indicated by arrows in Fig. 9.

50 In the use of the apparatus, one or both rollers are driven to move the upper stretch of the band lengthwise, and tufted thread 20, 21 led from a suitable source is passed between the crosswise reciprocatory presser-block 33 and the endless band 30. The tufted thread, in its passage, is 55 pressed and rolled in the manner hereinbefore described into the form of rolled yarn 22, and this yarn passes, preferably by way of a suitable tension device (not shown), to a take-up motion, 60 the tension device exercising a pull sufficient to maintain the yarn substantially straight during the pressing and rolling operation.

65 It will be clear that a number of tufted threads may be supplied to the apparatus and operated upon simultaneously in order to form a like number of rolled yarns.

In the use of the apparatus above described, 70 there will not only be imparted to the tufts a combined pressing and rolling operation, but also a lengthwise drag, on account of the presser-

block being stationary endwise. If it be desired to obviate the production of this drag, provision may be made for moving, in unison, both members endwise while the thread passes between them. A form of apparatus having such provision will now be described with reference to Figs. 10 and 11.

As shown in Figs. 10 and 11, two superposed endless bands 30, 40 respectively pass around pairs of rotatable rollers 31, 31, and 41, 41 the 80 rollers constituting one pair being adjustable towards and away from the other pair (for example, by a screw-adjustment interconnecting the bearings of the rollers). The adjacent stretches of the two bands pass respectively above and below two presser-tables 32, 42 which are adjustably pressed towards one another by weights or springs in any suitable manner and which serve to press the said stretches towards one another. One of the bands and its roller receive, in addition to the necessary longitudinal thread-conveying movement, a crosswise reciprocatory motion (by any suitable means, such as a cam device or an adjustable eccentric device).

In the use of the apparatus, rollers of both 100 pairs are driven so that the contiguous stretches of the bands move at the same speed towards the take-up end, and tufted thread is passed between these stretches. In the passage of the tufted thread, the tufts receive, in combination with the 105 pressure action, a purely transverse rolling action, with the result that no lengthwise drag is imparted to them.

If desired, both bands may receive a differential crosswise reciprocatory motion; and provision may be made to stop the rotational movement of the rollers supporting one or both of the bands.

Yet another form which the apparatus may take is illustrated in Fig. 12, in which form provision is made to take the original twist from the tufts as a preliminary operation. This provision takes the form of a preliminary unit comprising two members 50, 51 presenting contiguous rubbing faces between which the tufted thread is 115 passed. The member 50 is a presser-block which receives a reciprocatory motion (by crank-and-connecting rod or other suitable mechanism) in a direction inclined to the direction in which the tufted thread passes between the members, the 120 inclined reciprocatory motion being indicated by arrows. The member 51 consists of a stationary table. Springs or weights may be provided to press the block 50 towards the table 51 so that the tufted thread, in its passage, is subjected to 125 an inclined rubbing action, the effect of which is to take the twist out of the tufts and set them closely against one another. The partially rolled tufted thread is then passed to a finishing unit 130 comprising apparatus such as hereinbefore described with reference to Figs. 8 and 9 for effecting a combined pressing and rolling action. The rubbing and rolling members of both units of the apparatus may be arranged to reciprocate in unison; that is, when one member moves in one 135 direction across the line of motion of the tufted thread and rolled yarn, the other moves in the same direction.

If desired, apparatus such as described with reference to Figs. 10 and 11 may instead be used 140 as the second unit.

A preliminary unit such as included in Fig. 12 is mainly intended for use in connection with tufted thread whose pile tufts are of "hard twist"—that is, tufts cut from tightly twisted 145 150

yarn—it being found that increased mechanical treatment is required for such thread to ensure adequate separation and proper spreading of the tuft fibres; and it is generally necessary to apply the said treatment in two different directions, as in the Fig. 12 arrangement. In connection with tufted thread whose tufts are of "soft twist"—that is, loosely twisted apparatus such as illustrated diagrammatically in Figs. 8 and 9 or Figs. 10 and 11 can be effectively employed without need for a preliminary unit.

The manufacture of the rolled yarn may be facilitated by steaming or vaporizing the threads (especially those of a "lively" fibre), or by sizing them before undergoing the rolling operation.

The new yarn differs materially from the ordinary round chenille in that the ends of the tufts are not radially exposed, the tufts intermingling with one another to form a felted or matted surface, and the round body of the yarn is not loose but compact.

Fabrics of various kinds can be made in usual and well known manner with the rolled yarn.

I claim:—

1. Round-section yarn consisting of a core and tufts which extend from said core, wind tightly around said core and inter-engage to form a felted surface.

2. Round-section yarn consisting of a core and fibrous tufts, in which yarn the tufts are attached to and extend from said core and wind themselves tightly around said core, the fibres of adjacent tufts intermingling so that said tufts intimately merge into one another and present a round, compact and felted surface.

3. Yarn which is made of chenille including a core and tufts extending from said core, and in which the tufts wind tightly around said core and inter-engage to form a felted surface.

4. Round-section yarn which is made of chenille including a core and fibrous tufts attached to and

extending from said core, and in which yarn the tufts wind themselves tightly around said core, the fibres of adjacent tufts intermingling so that said tufts intimately merge into one another and present a round, compact and felted surface.

80

5. A method of manufacturing yarn from tufted thread including a core with fibrous tufts attached thereto, which method consists in simultaneously rolling and pressing said tufted thread transversely thereof until the tufts wind tightly around the core with the fibres composing adjacent tufts intermingled.

85

6. A method of manufacturing round-section yarn from tufted thread such as chenille including a core with fibrous tufts attached thereto, which method consists in simultaneously rolling and pressing said tufted thread transversely thereof until the tufts wind tightly around the core with the fibres composing adjacent tufts intermingled to present a round, compact and felted surface.

90

7. A method of manufacturing yarn from tufted thread including a core with tufts attached thereto, which method consists in applying transverse rolling pressure as a first operation to spread the tufts, and applying transverse rolling pressure as a second operation to said tufted thread until the spread tufts wind tightly around the core and inter-engage.

100

8. A method of manufacturing round-section yarn from tufted thread such as chenille including a core with fibrous tufts attached thereto, which method consists in simultaneously rolling and pressing said tufted thread transversely thereof as a first operation to spread the fibres of the tufts, and simultaneously rolling and pressing said tufted thread transversely thereof as a second operation until the spread fibres of the tufts wind tightly around the core and intermingle to present a round, compact and felted surface.
